AWNNG CLIP

Lionel J. Babin, Jr., Houma, La., assignor of
eighty-five per cent to Lionel J. Babin, and fif-
teen per cent to Dudley Melancon, both of
Houma, La.

Application December 27, 1949, Serial No. 135,208

5 Claims. (Cl. 20—57.5)

1

This invention appertains to a rigid type awning structure and more particularly relates to a novel connecting or locking means for the valance of the awning or the relatively short vertically depending fringe portion on the front of the awning structure.

The primary object of this invention is to form the awning surface panels with self contained locking means so that the panels can be readily and conveniently connected together in a properly spaced and arranged assembly without the use of headed fasteners or the like.

These and ancillary objects and structural features of merit are attained by this invention, the preferred embodiment of which is set forth in the following description and illustrated in the accompanying drawing, wherein:

Figure 1 is a fragmentary elevational view;

Figure 2 is a transverse sectional view taken on line 2—2 of Figure 1; and

Figure 3 is a fragmentary sectional view taken on line 3—3 of Figure 1.

In the accompanying drawing, the awning structure 10 includes a plurality of bottom metal panels 12 having parallel upstanding side walls 14 formed on their opposing side edges and terminating at their upper edges in inwardly directed flanges 16. Inverted U-shaped upper panels 18 are provided and are adapted to be positioned on the flange on the adjacent side walls of adjoining lower panels 12, which are laterally spaced so that the upper and lower panels are in spaced staggered relationship. The walls 20 of the upper panels 18 are parallel and terminate in lateral inwardly directed flanges 22. As seen in Figure 1, the front ends of both the upper and lower panels are bent downwardly at an obtuse angle to form a depending vertical front fringe or valance 24, with the bent ends of the panels being held together in a manner as taught by this invention.

Slots 26 are formed in the web portions of each of the lower panels and portions are struck upwardly from the surface and paralleling the axis of the panels to form openings 28 and ears 30 which are spaced from and parallel with the upper surface of the web portions. Thus, the flanges 22 on the walls of the upper panels fit into the openings and are frictionally fitted under the ears 30 which face inwardly and are positioned adjacent to the walls 20.

Having described the invention, what is claimed as new is:

1. A rigid type metal awning including stag-
gered U-shaped lower panels and inverted U-
shaped upper panels overlying the lower panels,
the web portions of the lower panels having slots
formed with upstruck overlying ears and the walls
of the upper panels terminating in lateral flanges
frictionally fitted under the ears.

2

2. A rigid type metal awning including stag-
gered U-shaped lower panels and inverted U-
shaped upper panels overlying the lower panels,
the web portions of the lower panels having slots
formed with upstruck overlying ears and the walls
of the upper panels terminating in lateral flanges
frictionally fitted under the ears, wherein said
slots are longitudinally spaced on the web por-
tions and extend axially of the web portions.

3. A rigid type awning comprising a first set
of channel shaped awning surface panels, each
of said panels including a web portion having up-
standing walls formed on the side edges there-
of; a second set of channel shaped panels, each
of said panels of the second set including a web
portion having upstanding walls formed on the
side edges thereof with lateral inwardly directed
flanges formed on the side walls; the panels of
the second set being inverted and overlapping
the panels of the first set with the web por-
tions of each panel of the second set resting
on the adjoining walls of adjacent panels of
the first set; the web portions of the panels of
the first set being formed with longitudinally dis-
posed elongated inwardly facing upstruck ears
defining elongated slots, with portions of the
flanges of the walls of the panels of the sec-
ond set being inserted under the ears.

4. A rigid type metal awning comprising a set
of U-shaped lower panels, a set of inverted
U-shaped upper panels overlying the lower panels
and staggered with respect thereto, the panels
of one of said sets having upstanding walls on
the side edges thereof, lateral flanges on said
side walls, the web portions of the other set of
panels having upstruck ears defining elongated
slots, said lateral flanges being received and re-
tained beneath said ears.

5. The combination of claim 4 wherein said
lateral flanges are directed inwardly of said up-
standing walls whereby said ears are housed be-
tween the webs and the upstanding walls of
a panel of each set.
